UNITED STATES PATENT OFFICE.

ARTHUR F. POOLE, OF KENILWORTH, ILLINOIS, ASSIGNOR TO REMINGTON ACCOUNT-
ING MACHINE CORPORATION, OF NEW YORK, N. Y., A CORPORATION OF NEW YORK.

CALCULATING MACHINE.

Application filed August 11, 1921. Serial No. 491,490.

To all whom it may concern:

Be it known that I, ARTHUR F. POOLE, citizen of the United States, and resident of Kenilworth, in the county of Cook and State of Illinois, have invented certain new and useful Improvements in Calculating Machines, of which the following is a specification.

This invention relates to improvements in calculating machines and it is especially adapted for machines which comprise both registering mechanism and key actuated recording mechanism. In the present instance it is shown applied to that variety of such machines which has long been known as the Remington-Wahl combined typewriting and calculating machine. The construction and operation of that machine are particularly described in Patent No. 1,270,471, issued June 25, 1918 to the Wahl Company, assignee of the inventor John C. Wahl.

To provide for the equipment of that machine with a clear-signal, two forms of signal-mechanism have been invented. One of these, the invention of Arthur F. Poole, is described in Patent No. 1,311,710, and the other, the joint invention of Hyman Golber and Arthur F. Poole, is described in an application for a patent, which was filed February 10, 1919, and bears the Serial Number 276,172. In the use of a machine embodying either of these forms of signal-mechanism the operator may neglect or forget to strike a key which is comprised in the signal-mechanism and on the operation of which the true effect of that mechanism depends.

The main object of the invention which is set forth and claimed herein is to provide the machine with means to warn the operator that he should strike such key at the end of a clearing operation, but the invention is not limited to that specific use.

This invention is shown and described in combination with the signal-mechanism of the above mentioned application, but may readily be combined with said patented signal-mechanism or other similar signal-mechanism, as the following description, it is believed, will make plain to any person skilled in the art.

The invention consists of features of construction, combinations and arrangements of parts, all of which are set forth herein and defined in the claims.

In the accompanying drawings which include eleven figures and which show, besides said Golber-Poole signal-mechanism, only so much of a Remington-Wahl machine embodying the claimed invention as it is regarded necessary to illustrate herein for the purpose of making the description of this invention plain:

Figure 1 is a side and sectional elevation of a portion of the machine; 65

Figure 2, is a side and sectional elevation of parts shown in Fig. 1, and of other parts;

Figure 3, a front and sectional elevation of a part of a totalizer and devices attached to it; 70

Figure 4, a face view of a typeblock and fragment of a type bar.

Figure 5, a face view of another typeblock and a fragment of the same type bar;

Figure 6, a diagrammatic front elevation 75 of a row of column totalizers, a cross totalizer, and a sheet of a bank ledger;

Figure 7, a side and sectional elevation of a fragment of the machine;

Figure 8, a horizontal section on plane 80 8-8, Fig. 7 of that fragment;

Figure 9, a similar horizontal section of that fragment, parts being shown in positions differing from those shown in Fig. 8;

Figure 10, a front elevation of a portion 85 of the same fragment; and

Figure 11, a plan of mechanism and horizontal section of a casing, constituting a portion of the cross totalizer.

Like reference numerals designate like 90 parts in different views.

The illustrated portions of the machine are shown as they appear when it is ready for use on special work and when the registering mechanism includes six column-to-talizers and a cross-footing totalizer. 95

Well known parts of the Remington-Wahl machine, which are shown, or partly shown, herein and described in said Patent No. 1,270,471 are the frame 10 of the typewriter, parts 11, 12, 13, 14 and 15 of the framework of the calculating machine which are rigidly secured together and affixed to the frame 10 by means of fastenings in which the screws 16 and 17, bracket 18, rivets 19 and bolt and nut 20 are included, the extension 21 of the typewriter-carriage, the main or vertical decimal carriage or truck 22 connected to extension 21 by bolt and nut 23, the secondary truck or cross-truck 24, the pick-up- 105 110

beam 25 by which the cross truck is connected to a column totalizer when this truck is drawn step-by-step from right to left, the pick-up guard 26, the master wheels 27 and 28, all of the other mechanism shown in Fig. 1 below the cross-totalizer 29 and in Fig. 2 below the column-totalizer 30, and all of the mechanism shown in cross-totalizer 29 (Fig. 1) except Golber-Poole signal-mechanism, 10 which is particularly described below. The column-totalizer 30 (Figs. 1, 2 and 6) and the five other column-totalizers 31, 32, 33, 34 and 35 (Fig. 6) are mounted on and attached to the truck 22 and each of them defines a calculating zone through which the carriage travels. The cross-totalizer 29 is mounted on and attached to the cross-truck 24. The mechanism in each of these column-totalizers is the same as that of the well 20 known Wahl totalizer, which is particularly described in said Patent No. 1,270,471. Cross-totalizer 29 contains the Wahl mechanism to which Golber-Poole mechanism has been added. Those parts of the Remington- 25 Wahl machine which are not shown herein are all described in the patent last above mentioned.

In totalizer 29 (Figs. 1 and 11) each of the gears 36, which are rigidly connected 30 with the numeral wheels 37 and driven, when they are actuated, by the master wheel 28 acting through the carrying gears 38 and intermediate gears 39, has one short tooth 40. The length of this short tooth is such 35 as not to prevent gears 39 from properly driving gears 36. The angularly movable comb 41 mounted in the framework of the totalizer on shaft 42 has prongs 43 equal in number to gears 36 and fast together. The 40 spring 44 attached to the framework and bearing against the back of one of these prongs tends to turn the comb from its normal position, which is that shown in Fig. 1. The relations of the short teeth 40 to the 45 numeral wheels 37 and prongs 43 of the comb are such that when the "0" of any numeral wheel is opposite the sight opening 45 in the casing of the totalizer the short tooth of the gear 36 affixed to that numeral 50 wheel is immediately in front of a prong 43. If a numeral wheel does not register "0" then a long tooth of the gear is immediately in front of the prong. Unless all of the 55 numeral wheels of the totalizer register "0," the spring 44 cannot turn the comb but merely presses a prong or prongs thereof against one or more of the long gear teeth. If all numeral wheels but one of the totalizer 60 register "0" and that wheel is turned until it also registers "0" the spring 44 turns the comb until it is arrested by the co-action of one or more of the short teeth 40 and one or more of the prongs 43.

The arm 46, fast on a part of comb 41, 65 stands directly behind the angular movable

latchbar 47. This bar is mounted on the stud 48, and the spring 49 is attached to the bar and to the pin 50 tends to swing the upper end of the bar backward. The stud 48 and pin 50 are fixed in the right side plate of the totalizer. This bar has the shoulder 51. The pin 52, fixed in this bar, extends through a slot in the right side plate of the totalizer and a little beyond the outer face of the side plate (Fig. 6) and to it is affixed the knob 52a. The latchbar 47 normally makes contact, a little below shoulder 51, with the front end of arm 53 of lever 54, the upper end of the bar being a short distance from arm 46 when the comb, latchbar and lever 54 are all in their normal positions. The lever 54 is mounted on the shaft 55, which supports one set of the swinging arms 56 comprised in the Wahl totalizer, and when this lever is in its normal position arm 53 rests on the collar 57 on the shaft 58 which supports the carrying gears 38. The spring 59, attached to arm 53 and to shaft 60 in the framework of the totalizer, tends to keep this lever in its normal position. In the other arm, or tail, 61 of the lever 54 is a slot 62 similar to those at the lower ends of the swinging arms 56 of the Wahl totalizer. This lever is close to the right side of the totalizer, its arm 53 being close to the carrying wheel 38 which is at the right end of the series of carrying wheels. The space occupied by the lever is called the sub-units place of the totalizer since its width is that of a decimal place and it is at the right of and next to the lowest or units decimal place of the totalizer. When the totalizer makes that step in which the carrying wheel of lowest order is disengaged from the master wheel 28, the front and rear walls of the slot 62 in the tail 61 of the lever are brought into alignment with the upright arm 63 of the master dog 64, which every Remington-Wahl machine contains when it includes a cross totalizer. The rearwardly projecting tooth 65 of the master dog extends under the rack 66 fast on the cross-truck 24 (Fig. 1). The dog is connected by the roller 67, mounted on it at its lower end, with the cam 68 having in it the slot 69 in which the roller loosely fits. The dog 64 and cam 68 are on the arbors 70 and 71 respectively, and these arbors are supported by and have bearings in parts of the framework. This cam is connected by the pin 72 to the link 73 which is pivoted to the arm 74 fast on shaft 75.

The master dog 64 is a duplicate of the master dog 76 (Fig. 2) which is supported by parts of the framework on the arbor 77 and has the upright arm 78 and rearwardly projecting tooth 79, and on which at its lower end is the roller 80. The tooth 79 extends under the rack 81 (Fig. 1) fast on

the vertical or main truck 22. The roller 80 fits loosely in the slot 82 of the cam 83, the arbor 84 of which is supported by and has bearings in the framework. The cam is connected by the pin 85 and link 86 to the arm 87 fast on the rock shaft to which the key actuated fan 88 and the nine other similar fans of the machine impart motion by acting on the rod or universal bar 89 mounted in arms 90 also fast on the rock shaft. The arm 91 fastened to this rock shaft at its right end by the screw 92, and the arm 93 fastened to the shaft 75 at its left end, are connected together by the link 94, these arms being parallel and of the same length so that the two shafts rock alike. The fan 88 is connected by the link 95 to the key lever 96. This is the key lever to which the "0" printing type bar 97 (Figs. 4 and 5) of the machine is connected. The typeblock of this type bar may be either the block 98 (Fig. 4) or the block 99 (Fig. 5). These blocks are alike except that block 98 has on it, in the upper case position, a clear-signal type 100, shown as an asterisk type, whereas block 99 has no upper case type.

On the fan 88 are the upper series of ratchet teeth 101, and lower series of ratchet teeth 102. When the key is depressed the full stroke pawl 103 acts on the teeth 101, and when the key rises the full stroke pawl 104 acts on the teeth 102. The arm 105, fast on the rock shaft to which arms 87, 90 and 91 are fixed, extends over the arm 106 rigidly attached to pawl 104, and as the key moves downward arm 105 acting on arm 106 forces pawl 104 out of the path of the teeth 102; and pawl 103 has an arm (not shown) in position to be acted on by arm 105 to release said pawl 103 during the up-stroke of the key.

The sector 107 which is mounted on the upper sector shaft of the machine, and which 45 drives master wheel 27 through intermediate gearing, gears 108 and 108^a comprised in that gearing, the lower sector shaft 109, the sector 110 which is mounted on shaft 109 and drives master wheel 28 through intermediate gearing, the gears 111 and 111^a included in this intermediate gearing, the arms 112 and 113 parallel, equal in length and fast on the upper and lower sector shafts respectively, the link 114 connecting these 55 arms together, the gooseneck 115 similar to eight others of a series, and the series of arms 116 which are fast on the upper sector shaft and on which the nine goosenecks act to impart different angular movements to 60 that shaft, can be identified readily, it is believed, as parts of the Remington-Wahl machine described in the aforesaid patent No. 1,270,471, and therefore it is regarded as unnecessary to describe herein more fully than 65 has been done, the construction of the mech-

anism which is composed of these parts. Suffice it to say that master wheel 27 can be turned for addition or subtraction by shifting gears 108 and 108^a so that one or the other of them meshes with sector 107, and 70 master wheel 28 can be similarly controlled by shifting gears 111 and 111^a. In practice, at the completion of a calculation a totalizer is cleared by setting its master wheel for subtraction and copying the total by striking the appropriate numeral keys.

That part of the mechanism of totalizer 29 which is Golber-Poole signal-mechanism, shown in their aforesaid application, consists of comb 41 in which arm 46 is included, 80 the latchbar 47 and the lever 54, arranged as described above and represented in Figs. 1 and 11. Totalizer 29, illustrated herein, and the single totalizer illustrated in that application are duplicates. Either may be substituted for the other and used at will as a column totalizer or a cross footing totalizer in any ordinary Remington-Wahl machine.

Whenever any numeral wheel of totalizer 29 is actuated by the depression of a key, both the main master dog 76 and the other, or secondary, master dog 64 are rocked soon after the key begins to move so that their upright arms 78 and 63 move forward and their teeth 79 and 65 engage racks 81 and 66 respectively. The numeral wheel is turned after the dogs engage, and while they continue to engage, the racks, but before the key reaches the end of its stroke. At the end of the key stroke the master dogs suddenly return to their normal positions, and then, as the key rises, the escapement acts, the carriage steps, trucks 22 and 24 are drawn to the left, the actuated numeral wheel is carried to the left of master wheel 28, and the next decimal place below that numeral wheel is brought into register with the master wheel.

When the totalizer 29 has been operated for the purpose of clearing it by subtracting the total, and has reached the position in which it stands when the sub-units decimal place is in register with the master wheel, the operator, to ascertain whether the totalizer is clear or not, should depress the case shift key of the typewriter and strike the clear signal key 96, and by the same act can record the clear signal at the right of the recorded total if the type bar 97 has on it the typeblock 98. The master dogs are rocked as above explained and the type bar 97 is actuated, during the downward movement of this key, but, this being the "0" key, the sector shafts are not turned since fan 88 does not act on any gooseneck. The master dog 64 acting through its forwardly moving upright arm 63 on lever 54 raises the front end of arm 53 of that lever above the level of shoulder 51 of latchbar 47. If 130

the totalizer is not clear the latchbar is then turned by spring 49 until the bar makes contact near its upper end with arm 46 of comb 41, and meanwhile shoulder 51 passes under 5 the front end of lever-arm 53. When the finger of the operator is removed from the key the latchbar prevents lever 54 from returning to its normal position and this lever, with which upright arm 63 of master dog 64 10 makes contact at the back of slot 62, prevents the master dogs from returning to their normal positions. Consequently trucks 24 and 22 and the typewriter carriage are locked, for teeth 65 and 79 of the master 15 dogs are kept engaged with the racks 66 and 81 on the trucks. Moreover, master dog 64 prevents cam 68, rod 89 and those parts of the mechanism which connect each with the other, from returning to their normal positions, so that pawl 103 remains engaged with 20 the last ratchet tooth of the series 101 and prevents fan 88 from turning backward, and therefore the key is held down. Hence the machine is so locked up as to render it useless until the locked parts are unlocked. 25 The operator perceiving this knows that the totalizer is not clear and that a mistake has been made. He then unlocks the locked parts by pulling knob 52^a forward, thus releasing lever 54 from latchbar 47, whereupon the lever 54, master dogs, fan 88, key lever 96 and other parts return to their normal positions, the escapement acts, and the typewriter carriage, trucks 22 and 24, and 30 the totalizer step to the left. Thereafter the gear shift is operated, the incorrect number recorded on the work sheet is added, the recorded number is erased, the gear shift is again operated, and the total then shown 35 by the register is subtracted and recorded. 40

When the correction has been made and the totalizer is clear and the sub-units decimal place has been brought into register with the master wheel, the clear signal key 45 should be actuated again to record a clear signal mark either by printing it in place of the previously printed mark if that was erased, or by printing it over that mark. In case the clear-signal type bar has on it 50 the typeblock 99 the clear signal mechanism operates as described except that a clear-signal mark is not recorded.

If a clearing operation is correctly performed, then as soon as the totalizer becomes clear spring 44 turns comb 41 as above explained, and the upper end of arm 46 is moved to and held against latchbar 47. Then spring 49 cannot turn the latchbar although the front end of arm 53 of lever 54 55 may be raised above the level of shoulder 51, for that spring is weaker than spring 44. Therefore, whenever the totalizer is clear, the latchbar does not prevent lever 54 from returning to its normal position after 60 that lever has been actuated by master dog

64, and the lever does not prevent the master dog or any other part of the clear-signal mechanism from returning to its normal position as soon as the key is allowed by the operator to rise, and during the upward 70 movement of the key the typewriter carriage, trucks and totalizer advance as they commonly do after a numeral wheel has been actuated. Then, if another key is struck, the desired action of the machine is obtained, or if the use of the machine is discontinued 75 it remains ready for use at any other time.

Obviously, an operator about to use the machine may ascertain whether the totalizer is clear or not by first setting it so that 80 sub-units place is in register with the master wheel and then striking the clear signal key and observing what follows.

By striking any numeral key when the totalizer is properly set, an operator could 85 find that the totalizer was or was not clear, but should any key of the series bearing the Figures 1 to 9 both inclusive be struck not only would the clear signal mechanism contained in the totalizer be actuated but a figure would be recorded and a gooseneck, the sector shafts, the sectors and other mechanism would be actuated idly.

If an operator using a Remington-Wahl 90 machine equipped with the Golber-Poole signal mechanism which has been above described, should not strike the clear signal key or otherwise test the totalizer at the conclusion of a clearing operation, an error made in an incorrect clearing operation 95 might cause much trouble, for not only would it affect the work then supposed to be finished but also, unless it should be discovered prior to a subsequent use of the machine, would affect later work.

The invention claimed herein, and comprising devices now to be described, is intended to render certain the discovery of error in an incorrect clearing operation before the totalizer can move again after it 100 makes the step in which the units carrying wheel 38 passes from engagement with the master wheel.

When the special work above referred to 105 is being done, the cross footing totalizer 29 is cleared by subtracting in that totalizer the amount of the total, and said total simultaneously is recorded in the column headed "Balance" on the sheet 117, and registered again by adding it in totalizer 30.

On the right wall 118 of this column totalizer is the latch 119 which forms one member of an automatic lock. This latch is attached to wall 118 by the headed stud 120 which is fixed in the wall and on which the latch may turn. To the pin 121 fixed in the latch and to the pin 122 fixed in the wall is connected the spring 123 which pulls on pin 121. The latch 119 comprises the rearwardly projecting upper portion 124, the 125

spur 125 and the tail 126. The spur 125 extends between teeth of rack 127 fast on truck 22 to which the totalizer 30 is attached. When the above described member of the lock is engaged with the other member, which is stationary, the position of the movable member 119 is that in which it is shown by Figs. 1, 2, 7, and 8.

The Remington-Wahl machine comprises an upwardly and forwardly extending bracket 128 rising from part 11 of the framework of the calculating mechanism. This bracket supports the roller by which truck 22 is guided at the top, and which is composed of the disk 129 and spindle 130 (Fig. 7). The spindle passes loosely through the bushing 131 which is fast in bracket 128 and has at its upper end the flange 132. The screw 133 driven tightly into spindle 130 forms at the upper end of the spindle a flange which rests on the bushing and keeps disk 129 close to the lower end of the bushing. According to the present invention, the stationary member of the lock and the pointer 134 are parts of one piece of stock, bent so that it fits on the top and front of the bracket 128, and drilled or punched so that it fits on the bushing 131. This member is composed of the parts 135, 136 and 137. The horizontal part 135 through which the bushing passes, extends between the flange of the bushing and top of the bracket and is fastened to the bracket by the screw 138 and bushing 131. The part 124 of latch 119 is adapted under certain conditions to be moved by spring 123 into the space 139 (Fig. 10) between the vertical parts 136 and 137 and thus to lock the truck 22 and the typewriter carriage against movement in either direction. On part 136 at the left edge thereof is the bevel 140, and on part 137 at the right edge thereof is the bevel 141, said bevels being so shaped that part 124 of latch 119 will slide over them without being arrested. The cam-shaped collar 142 fits loosely on bushing 131 and between bracket 128 and disk 129. When this collar is in its normal position the projection 143 thereof is in contact with part 137 of the stationary member of the lock and extends a little in front of the plane of its front face (Figs. 9 and 10). The spring 144, which is attached by screw 145 to bracket 128 and enters a hole in the collar, tends to keep the collar in its normal position. The projection 143 is so shaped that part 124 of latch 119 will slide over it during the motion of the carriage toward the right and will be prevented thereby from entering the space 139; but during travel toward the left, said part 124 will strike the abrupt portion of projection 143, turn the collar 142, and snap into space 139, as shown in Figs. 7 and 8. This occurs on that step of the carriage which follows the writing of the last digit

of the "Balance" and registering said digit in totalizer 30, so that at that time the carriage becomes locked in the sub-units position of totalizer 30.

The tail 126 of member 119 of the lock extends behind the upper end of the releasing device 146 (Figs. 1, 2 and 3), and normally is kept by the action of the spring 123 in contact with it. Said releasing device is attached to wall 118 of the totalizer by the headed and shouldered screw 147 on which the device may turn. The spring 148 connected at one end to pin 149 fixed in this device, and at the other end to pin 150 fixed in the wall, pulls on pin 149 and normally keeps the device in contact with pin 151 also fixed in the wall. The lower portion 152 of this device extends into the recess 153 where the lower edge of wall 118 has the shape shown in Figs. 1 and 3, and this part 152 of the releasing device is in the sub-units decimal place of the totalizer and so located therein that it rests directly in front of and close to the upright arm 78 of master dog 76 when the sub-units decimal place is in register with that master dog. In short, part 152 is in position to be operated by master dog 76.

On the heel 154 of totalizer 30 is the lug 155 (Figs. 3, 2 and 1) which is offset, so that it is located close to and on the right of the sub-units decimal place. This lug engages with the pick-up-beam 25 by which truck 24 is drawn step-by-step to the left when numbers are registered in the cross totalizer. Pick-up guard 26 has to this lug the relation which it commonly has to the heel of an ordinary column totalizer. Totalizer 30 is provided with this off-set lug to compensate for a slight difference between the cross totalizer 29 and the common Wahl totalizer in respect to the location of latch 156 (Fig. 1), which fits in recess 157 in plate 158 fast on truck 24 when the totalizer is locked to the truck. The right wall of totalizer 29 is separated from the carrying wheel 38 of lowest order by the sub-units decimal place, in which the arm 46 of comb 41, latch bar 47 and lever 54 are located. Latch 156 is close to the inner face of that wall so that the latch also is in the sub-units decimal place, and the location of totalizer 29 on truck 24 is one decimal place to the left of that of a common Wahl totalizer attached to this truck, the latch of the latter being in the units instead of the sub-units decimal place. Therefore, if the heel of totalizer 30 was exactly like that of a common Wahl totalizer in respect to both form and location, cross totalizer 29 would be nearer by a decimal place than it should be to totalizer 30 when the heel of the latter was engaged with the pick-up-beam. But when the off-set lug 155 is engaged with the pick-up-beam, whatever decimal place of

- 8
- column totalizer 30 may be in register with master wheel 27 the like decimal place of cross totalizer 29 is in register with master wheel 28.
- 5 To adapt column totalizers 31, 32, 33, 34 and 35 to engage with the pick-up-beam when each is at the proper distance from cross totalizer 29, the right side plate of each of these column totalizers is put at the distance of a decimal place from the carrying wheel of lowest order, i. e., just at the right of the sub-units decimal place, indicated in Fig. 6 by reference numeral 159. That side plate, including the heel, is like the right side plate of a common Wahl totalizer.
- 10 The arm 160 with roller 161 mounted thereon (Fig. 6), and the cam plates 162 attached to column totalizers 30, 31, 32 and 33, and arranged to act on roller 161 and depress it as they are drawn over it in the operation of the machine, are well known parts of the gear-shifting mechanism of the Remington-Wahl machine, which mechanism is described in the above mentioned
- 15 25 Patent No. 1,270,471 and by means of which mechanism the machine may be put in condition to add, or in condition to subtract, or in condition to add in one totalizer and subtract in another. The cams 162 here shown are adapted to set the actuator of cross totalizer 29 for subtraction. The machine herein described, when it is in use on the special work above mentioned, is in such condition that numbers are added in each of the
- 20 30 35 column totalizers, and a number added in totalizer 30 or 31 or 32 or 33 is simultaneously subtracted in the cross totalizer 29, and a number added in totalizer 34 or 35 is simultaneously added in the cross totalizer.
- 40 45 50 55 60 65 70 75 80 85 90 95 100 105 110 115 120 125 130
- 40 Ledger sheet 117 (Fig. 6) shows entries made in an account, of transactions dated December 10, 17 and 18, 1920. The sheet indicates that on December 10 the deposit, or sum of the deposits, and the balance were equal, each being 546.27. That would be the case if the account had then been opened, on the deposit by J. Doe of 546.27, and if it had not become active until December 17. When the operator makes the record for December 17 the only entries which he finds on the sheet are "Dec. 10, 1920," and "546.27" appearing under "Deposits", and "546.27" appearing under "Balance." He puts the sheet in the machine and, supposing that he does the work correctly, adjusts it on the platen 163 and writes "546.27" under "Old balance." That amount is simultaneously added both in column totalizer 35 and cross totalizer 29, and if the cross totalizer was clear as it should have been, it then registers 546.27. Next, he line spaces and draws the carriage to the right, and on the new line records the date (written twice), the amounts of checks cashed and the amount of deposits. The cross totalizer then registers
- the difference between $546.27 + 100$ and $27.50 + 13.85$, to wit, 604.92. The operator, finding this to be so by looking at the cross totalizer, writes "604.92" under "Balance." Simultaneously this amount is subtracted in the cross totalizer, which therefore is left clear. He should then prove that the cross totalizer is clear by depressing the case shift key and striking the clear-signal key and printing the clear-signal mark 165 at the right of "604.92" in column headed "Balance,"—in other words, in the sub-units position of said column. After this the sheet is removed from the machine. It will be perceived that the machine is set up to go through a regular program of calculating and recording operations, as just described. When the record for Dec. 18, is made, first the amount of the balance 604.92 is written under "Old balance" and then the numbers which appear on the next line are written in order. After the writing and registering of the amount of the last check, viz, 63.50 the cross totalizer will show the new balance 384.32. This amount is copied in the column headed "Balance" and the cross totalizer is thereby cleared. Then, after the clear-signal key is or should have been struck to prove that the cross totalizer is clear, the sheet is removed from the machine. In Fig. 6 the parts are shown in the positions they occupy after the writing of the balance, 384.32, and before the striking of the clearance proof key 96.
- 100 105 110 115 120 125 130
- ..Whenever the amount of a balance registered in the cross totalizer is being written on the sheet under the heading "Balance," part 124 of latch 119 carried by totalizer 30 is forced against and across the bevel 141 of part 137 of the stationary member of the above described lock, the latch then turning slightly on pin 120 and the spring 123 being stretched. When the units decimal place gets into register with master wheel 27, part 124 of the latch is close to or in contact with part 143 of collar 142, and in the next step of the carriage and totalizer, that being the step in which the sub-units decimal place is brought into register with the master wheel, the latch turns the collar by pushing the part 143 to the left, and at the end of the stepping movement the latch is turned by spring 123 so that part 124 of the latch enters space 139, between parts 136 and 137 of the other member of the lock. The latch in thus acting on collar 142 bends spring 144 and turns the collar to the position in which it is shown in Fig. 8. On the engagement of latch 119 with the stationary member of the lock as described, of course totalizer 30, truck 22 and the typewriter carriage are all locked, and they cannot be unlocked by depression of the space key or any of the letter keys of the machine. But they can be unlocked by a stroke of the

clear-signal key if the cross totalizer is clear. The operator knowing that the machine is automatically locked at the end of each operation in which the cross totalizer is or should be cleared, and probably noticing each action of latch 119 as it engages with the other member of the lock, is warned that he should strike the clear-signal key to avoid the risk of finding the machine locked when he shall start to make the next record. Should he then find the machine locked he will then be notified that an error has been made in the last record and be put to extra trouble in correcting it. This warning or notification of error is due wholly to the presence of the locking mechanism associated with the totalizer 30, and consisting of the latch 119 and other member of the described lock and the releasing device 146. In the Golber-Poole invention, referred to above, there is nothing to prevent the operator from forgetting or neglecting to strike the clearance proof key 96, and should he fail to strike this key an error might result. In my herein described invention the mechanism associated with the totalizer 30, by locking the carriage, warns the operator that he should press, or notifies him that he should have pressed, this key.

As the clear-signal key descends when it is struck to unlock the locked parts of the machine, and as master dog 64, actuated by the clear signal key, is turning lever 54 in totalizer 29 as above described, arm 78 of master dog 76, also actuated by the clear signal key, forces part 152 of releasing device 146 forward, so that latch 119 is turned, by the action of the releasing device on tail 126 of the latch, until part 124 of said latch is withdrawn from slot 139 and part 143 of collar 142 escapes from part 124 of the latch. Immediately thereafter the collar returns to its normal position under the action of spring 144, part 143 passing behind part 124 of the latch (Fig. 9) and preventing said latch from re-entering slot 139. If the cross totalizer is clear the master dogs return to their normal positions at the end of the downward movement of the key, and as the key rises the escapement acts and the carriage and totalizer step. But if the cross totalizer is not clear, lever 54, as above explained, prevents master dog 64 from returning to its normal position, and the trucks are locked by teeth 65 and 79 of the master dogs which are then engaged with the racks 66 and 81 on the trucks. Then the operator, thus notified that he has made a mistake, pulls forward knob 52^a on latch bar 47, thus releasing lever 54 and unlocking the machine, whereupon he makes the correction before the sheet is withdrawn from the machine.

Whenever latch 119 passes the stationary member of the lock as truck 22 moves from

left to right, part 124 of the latch is forced forward by bevel 140 and is prevented from entering space 139 by part 143 of collar 142.

To facilitate the mounting and adjustment of totalizer 30 on and the removal of it from the truck, latch 119 is provided with the projection, or finger piece 164, which may be pulled forward and held so that spur 125 shall clear rack 127.

Although the special work above described is preferably done with a machine that includes the six column totalizers shown herein, it usually being desirable to register the column totals, yet the records could be made by operating the machine as above described if any or all of the totalizers 30, 31, 32, 33, 34 and 35 should be replaced with dummies. The clear-signal mechanism and above described lock would perform their functions if latch 119 and releasing device 146 were to be mounted on a dummy instead of on totalizer 30. A dummy comprises the frame or casing and the truck-engaging latch of a totalizer, the casing not containing registering mechanism. A dummy, as well as a totalizer, supported by truck 22, if latch 119 and releasing device 146 were mounted on the casing, would adjustably connect the latch and releasing device to the truck, and would properly engage with the pick-up beam to enable stepping movements to be imparted to the cross truck and cross totalizer.

Various changes may be made without departing from my invention.

What I claim as new and desire to secure by Letters Patent, is:—

1. In a calculating machine, the combination with a traveling carriage, a totalizer, an actuator for said totalizer, and clearance-proof mechanism including a key, of means for automatically locking an essential part of the machine at a predetermined point in the travel of said carriage, and means whereby said key releases the lock.

2. In a calculating machine, the combination with a carriage traveling through a series of computing zones, a totalizer capable of registering numbers in each of said zones, and clearance-proof mechanism for said totalizer including a key, of means for automatically locking an essential part of the machine at a predetermined one of said zones, and means whereby said key releases said lock.

3. In a calculating machine, the combination with a carriage, a totalizer, numeral keys for operating said totalizer, and a universal bar for said keys, of means for locking said carriage at a predetermined point in its travel, clearance proof mechanism for said totalizer including a key which operates said universal bar, a dog operated by said universal bar, and releasing means for said lock including a part which at said pre-

100

105

110

115

120

125

130

determined point of carriage travel is in co-operative relation to said dog.

4. In a calculating machine which embodies key-actuated recording mechanism in which a carriage is included, the combination of an automatic lock which acts on the carriage and by which movement of the carriage in either direction is prevented and the automatic action of which is controlled by the carriage, and key-operated mechanism to unlock the carriage.

5. In a calculating machine which embodies key-actuated recording mechanism in which a carriage is included, the combination of an automatic lock one member of which has a stationary support and the other member of which is mounted on a support to which motion is imparted by the carriage, and key-operated mechanism to force one member of the lock from the other member.

6. In a calculating machine which embodies key-actuated recording mechanism in which a carriage is included, the combination of an automatic lock which acts on the carriage and the automatic action of which is controlled by the carriage, and mechanism which constitutes a clear-signal and which includes a key and means actuated thereby to unlock the lock.

7. In a calculating machine which embodies key-actuated recording mechanism in which a carriage is included, the combination of an automatic lock one member of which has a stationary support and the other member of which is mounted on a support to which motion is imparted by the carriage, and mechanism which constitutes a clear-signal and which includes a key and means actuated thereby to force one member of the lock from the other member.

8. In a calculating machine which embodies key-actuated recording mechanism in which a carriage is included, the combination of an automatic lock which acts on the carriage and the automatic action of which is controlled by the carriage, and mechanism which constitutes a clear-signal and a part of which is a mark-printing device and which includes a key and means actuated thereby to force one member of the lock from the other member.

9. In a calculating machine which embodies key-actuated recording mechanism in which a carriage is included, the combination of an automatic lock one member of which has a stationary support and the other member of which is mounted on a support to which motion is imparted by the carriage, and mechanism which constitutes a clear-signal and a part of which is a mark-printing device and which includes a key and means actuated thereby to force one member of the lock from the other member.

65 10. In a calculating machine which em-

bodies a stepping part and an escapement whereby the stepping movement thereof is controlled, the combination of an automatic lock which holds said part fast in a particular one of the positions to which said part steps and one member of which lock is mounted on said part and the other member of which has a stationary support, and key-operated mechanism to force one member of the lock from the other.

11. In a calculating machine which embodies a part that has a stepping movement, the combination of an automatic lock one member of which is mounted on said part and the other member of which has a stationary support, a releasing device mounted on said part and adapted to force one member of the lock from the other, and key-actuated mechanism comprising a part to actuate the releasing device.

12. In a calculating machine which embodies a part that has a stepping movement, the combination of an automatic lock one member of which is mounted on said part and the other member of which has a stationary support, and mechanism which constitutes a clear-signal and which includes a key and means actuated thereby to force one member of the lock from the other member.

13. In a calculating machine which embodies a part that has a stepping movement, the combination of an automatic lock one member of which is mounted on said part and the other member of which has a stationary support, a releasing device mounted on said part and adapted to force one member of the lock from the other, and mechanism which constitutes a clear-signal and which includes a key and means connected therewith to actuate the releasing device.

14. In a calculating machine which embodies a decimal-truck, an escapement, and key actuated recording mechanism that includes a stepping carriage to which the truck is connected and the stepping movement of which is controlled by the escapement, the combination of a lock which holds the truck fast in a particular one of the positions to which the truck steps and one member of which lock is supported by the truck and the other member of which has a stationary support, and key operated mechanism to force one member of the lock from the other member.

15. In a calculating machine which embodies a traveling totalizer, an actuator past which the totalizer travels, and a traveling part to which the totalizer is connected when it is in use, the combination of a lock one member of which is supported by said traveling part and the other member of which has a stationary support and is located where the traveling member will engage with it when the sub-units decimal

- place of the totalizer is in register with the actuator, and key operated mechanism to force one member of the lock from the other member.
- 5 16. In a calculating machine which embodies a traveling totalizer, an actuator past which the totalizer travels, and a traveling part to which the totalizer is connected when it is in use, the combination of a lock 70
10 one member of which is supported by said traveling part and the other member of which has a stationary support and is located where the traveling member will engage with it when the sub-units decimal
15 place of the totalizer is in register with the actuator, key operated mechanism to force one member of the lock from the other member, and mechanism made effective by the totalizer unless it is in the cleared state
20 to preclude movement from a certain position of one of the parts of this key operated mechanism.
17. In a calculating machine which embodies a traveling totalizer, an actuator past 75
25 which the totalizer travels, a device which has a stepping movement and to which the totalizer is connected when it is in use, and a decimal carriage to which said device is adjustably attached, the combination of a
30 lock one member of which is supported by said device and the other member of which has a stationary support and is located where the traveling member will engage with it when the sub-units decimal place of
35 the totalizer is in register with the actuator, and key operated mechanism to force one member of the lock from the other member.
18. In a calculating machine which embodies a traveling totalizer, an actuator past 80
40 which the totalizer travels, a device which has a stepping movement and to which the totalizer is connected when it is in use, and a decimal carriage to which said device is adjustably attached, the combination of a lock 85
45 one member of which is mounted on said device and the other member of which has a stationary support and is located where the movable member will engage with it when the sub-units decimal place of the totalizer is in register with the actuator, key operated mechanism to force one member of the lock from the other member, and mechanism made effective by the totalizer unless it is in the cleared state to preclude movement from a certain position of one of the parts of this key operated mechanism.
19. In a calculating machine, the combination of registering mechanism, clearance 90
60 proof mechanism including a key, an automatic lock, and a releasing device for said lock, operated by said key.
20. In a calculating machine, the combination of registering mechanism, an automatic lock, a releasing device, the lock being 95
65 effective when its members are engaged to prevent operation of the machine, key operated mechanism comprising a part to actuate said releasing device, and mechanism made effective by the registering mechanism unless it is in the cleared state to preclude movement from a certain position of said part of the key operated mechanism.
21. In a calculating machine, the combination of registering mechanism, an automatic lock, a releasing device, the lock being effective when its members are engaged to prevent operation of the machine, key operated mechanism comprising a part to actuate said releasing device, and mechanism made effective by the registering mechanism unless it is in the cleared state to preclude movement of said part of the key actuated mechanism immediately after the releasing device has been actuated by it.
22. In a calculating machine which comprises a part that has a stepping movement, the combination of an automatic machine-lock which acts on and prevents movement in either direction of said stepping part and one member of which has a stationary support and the automatic action of which is controlled by said stepping part, and key operated mechanism to force one member of the lock from the other member.
23. In a calculating machine which comprises a part that has a stepping movement, the combination of registering mechanism, an automatic machine-lock one member of which has a stationary support and the automatic action of which is controlled by said stepping part, key operated mechanism to force one member of the lock from the other member, and mechanism made effective by the registering mechanism when a clearing operation is incorrectly performed to preclude movement from a certain position of a part of this key operated mechanism.
24. In a calculating machine which comprises a traveling totalizer, a separate totalizer frame, and a traveling part to which the totalizer frame is attached and to which said totalizer is connected when it is in use, the combination of a lock one member of which is supported by said totalizer frame 100
110 and the other member of which has a stationary support, and key operated mechanism to force the movable member of the lock from the stationary member.
25. In a calculating machine which comprises a traveling totalizer, a totalizer frame, and a traveling part to which the totalizer frame is attached and to which said totalizer is connected when it is in use, the combination of a lock one member of which is supported by said totalizer frame and the other member of which has a stationary support, key operated mechanism to force one member of the lock from the other member, and mechanism made effective by said totalizer 115
120
125
130

when a clearing operation is incorrectly performed to preclude movement from a certain position of a part of this key operated mechanism.

- 5 26. In a calculating machine which comprises a traveling part that has recesses in it, the combination with said part of a lock one member of which is supported by the traveling part and the other member of 10 which has a stationary support, and key operated mechanism to force one member of the lock from the other, in which key operated mechanism is included a dog permanently located on a stationary support and 15 having a tooth arranged to enter one of the recesses in said traveling part as the key is depressed.
27. In a calculating machine which comprises a traveling totalizer and a traveling 20 part from which the totalizer derives motion and which has recesses in it, the combination of a lock one member of which is supported by said traveling part and the other member of which has a stationary support, 25 key-operated mechanism to force one member of the lock from the other, in which key operated mechanism a dog permanently located on a stationary support and movable at the depression of the key into one of the 30 recesses in said traveling part is included, and mechanism made effective by said totalizer when a clearing operation is incorrectly performed to preclude movement of the dog from the recess.
- 35 28. In a calculating machine which comprises a cross totalizer, a totalizer frame to which the cross totalizer is connected when it is in use, and a truck to which said totalizer frame is adjustably attached and which 40 has recesses in it, the combination of a lock one member of which is mounted on said totalizer frame and the other member of which has a stationary support, and key operated mechanism to force one member of 45 the lock from the other, in which key operated mechanism is included a dog permanently located on a stationary support and movable at the depression of a key into one of the recesses in the truck.
- 50 29. In a calculating machine which comprises a cross totalizer, a totalizer frame to which the cross totalizer is connected when it is in use, and a truck to which said totalizer frame is adjustably attached and which 55 has recesses in it, the combination of a lock one member of which is mounted on said totalizer frame and the other member of which has a stationary support, key operated mechanism to force one member of the 60 lock from the other, in which key operated mechanism a dog permanently located on a stationary support and movable at the depression of a key into one of the recesses in the truck is included, and mechanism made 65 effective by the cross totalizer when a clearing

ing operation is incorrectly performed to preclude movement of said dog from the recess.

30. In a calculating machine which comprises a main truck, a secondary truck that derives motion therefrom, a totalizer frame attached to the main truck, and a cross totalizer attached to the secondary truck, each truck having recesses in it, the combination of a lock one member of which is mounted on said totalizer frame and the other member of which has a stationary support, key operated mechanism in which a main dog and a secondary dog each permanently mounted on a stationary support are included, the main dog being co-operative with other parts of this mechanism to force one member of the lock from the other and having a tooth that simultaneously enters one of the recesses in the main truck, and the secondary dog having a tooth that simultaneously enters one of the recesses in the secondary truck, and mechanism made effective by the cross totalizer when a clearing operation is incorrectly performed to preclude movement from a certain position of said secondary dog.

31. In a calculating machine which comprises a main truck, a secondary truck that derives motion therefrom, a totalizer frame attached to the main truck, and a cross totalizer attached to the secondary truck, each truck having recesses in it, the combination of a lock one member of which is mounted on said totalizer frame and the other member of which has a stationary support, key operated mechanism in which a main dog and a secondary dog each permanently mounted on a stationary support are included, the main dog being co-operative with other parts of this mechanism to force the movable member of the lock from the other and having a tooth that simultaneously enters one of the recesses in the main truck, and the secondary dog having a tooth that simultaneously enters one of the recesses in the secondary truck, and mechanism made effective by the cross totalizer when a clearing operation is incorrectly performed to prevent movement of the dogs from the recesses in the trucks.

32. In a calculating machine comprising key actuated parts and a totalizer frame which may or may not contain registering mechanism, the combination of a latch mounted on the totalizer frame, and a device also mounted on the totalizer frame and arranged to act on the latch and having a portion that at times extends into the path of one of the key actuated parts of the machine.

33. In a calculating machine comprising key actuated parts and a traveling member, the combination of a latch mounted on the traveling member, and a device also mounted

on the traveling member and arranged to act on the latch and having a portion that at times extends into the path of one of the key actuated parts of the machine.

- 5 34. In a calculating machine comprising key actuated parts and a traveling totalizer frame which may or may not contain registering mechanism, the combination of a latch mounted on the totalizer frame, and a
10 device also mounted on the totalizer frame and adapted to act on the latch and having a portion that rests in the path of one of

the key actuated parts of the machine whenever the traveling totalizer frame reaches a certain predetermined position.

Signed at the borough of Manhattan, city of New York, in the county of New York and State of New York, this 10th day of August, A. D. 1921.
